UNITED STATES PATENT OFFICE.

ANGELO PERRI, OF BELLINGHAM, MASSACHUSETTS, ASSIGNOR TO REECE SHOE MACHINERY COMPANY, OF BOSTON, MASSACHUSETTS, A CORPORATION OF MAINE.

MACHINE FOR LASTING STITCHED-DOWN SHOES.

1,398,528.

Specification of Letters Patent. Patented Nov. 29, 1921.

Application filed March 3, 1921. Serial No. 449,414.

To all whom it may concern:

Be it known that I, ANGELO PERRI, a citizen of the United States, and resident of Bellingham, county of Norfolk, State of 5 Massachusetts, have invented an Improvement in Machines for Lasting Stitched-Down Shoes, of which the following description, in connection with the accompanying drawing, is a specification, like characters on the 10 drawing representing like parts.

This invention relates to a machine for lasting stitched-down shoes and particularly to a lasting machine of that type which has a member or element against which the shoe 15 is held during the lasting operation and which operates to tuck or press the upper into the angle between the side of the last and the projecting margin of the sole, and a beater co-operating with said member to 20 beat or press the marginal portions of the upper and sole together.

The feature of the present invention relates to an improvement in the tool or element operating to press the upper into the 25 angle between the sole and the side of the last which tool accomplishes its function without distorting or wrinkling the upper as the shoe is fed past the tool. This end is accomplished by providing a rotary tool or 30 member and also by providing means for positively rotating it so that its action against the upper will counteract any tendency to distort the upper due to the feeding movement of the shoe.

35 In order to give an understanding of the invention I have illustrated in the drawings a selected embodiment thereof which will now be described, after which the novel features will be pointed out in the appended 40 claims.

Figure 1 is a side view of a machine embodying my invention.

Fig. 2 is a front view thereof.

Fig. 3 is a top plan view.

45 Fig. 4 is an enlarged section on the line 4—4, Fig. 3.

Fig. 5 is a section on the line 5—5, Fig. 4.

Fig. 6 shows the manner in which the rotating tool operates.

50 In the drawings which show a portion of a stitched-down shoe being lasted, 1 indicates the sole of the shoe, 2 indicates the upper, 3 the last and 4 indicates the marginal portion of the upper which overlies the marginal 55 portion of the sole.

The machine herein shown comprises a work-supporting member against which the upper face of the projecting portion of the sole of the shoe is held, and a beater or presser element co-operating with said work-supporting member to press together the marginal portion 4 of the upper and the marginal portion of the sole. This work-supporting member comprises a disk-like member 5 and a bed member 6, the latter 60 being received in a recess 7 formed in the under side of the member 5 and the under face of the two members 5 and 6 forming a recess against which the shoe is held. The beater or presser member is shown at 8 and 65 it is mounted to reciprocate toward and from the work-supporting member thereby to press the marginal portions of the upper and sole together as usual in lasting machines of this type. 75

These parts are supported on a suitable frame 9. The beater 8 is carried by a slide 10 that is slidably mounted in ways formed in a carriage 11 that in turn is constructed to reciprocate vertically of the frame 9. 80 The slide 10 is yieldingly connected to the carriage and for this purpose the slide is provided with an apertured boss 12 through which extends an adjusting screw 13 that is screw-threaded into the carriage 11, said 85 screw carrying a spring 14 which provides the yielding connection between the slide and the carriage. The carriage is provided with rack teeth 15 which are engaged by teeth formed on a lever 16 pivoted to the 90 frame at 17 and said lever is actuated from a crank pin 18 on a driving shaft 19, said pin being connected to the lever by the link 20.

The carriage 11 is provided with a trimming knife 21 which co-operates with the bed 95 member 6 to trim or rough round the sole. The parts as thus far described, with the exception of the member 5, are substantially the same as shown in the co-pending application of Benjamin S. La Fleur, Serial No. 100 416,605, filed Oct. 13, 1920 and in the operation of the device the shoe is held as shown in Figs. 1 and 4 so that the edge member 5 will engage the upper in the angle between the side of the last and the projecting margin 105 of the sole, and as the shaft 19 is rotated the carriage 11 will be reciprocated vertically and during each upward movement the beater will first be brought against the under face of the sole thereby pressing the 110

marginal portions of the sole and upper together, and while such portions are being thus pressed together the carriage will have its final upward movement to cause the knife 21 to trim or rough round the sole.

In this invention the member 5 is mounted in a stationary support 22 which is adjustably secured to the frame by means of a clamping screw 23 which operates through a slot 24 formed in the support 22. This adjustment is provided so that the operating edge of the member 5 may be adjusted nearer to or farther from the cutting knife 21, thus providing for trimming the sole so as to leave the desired width projecting beyond the last.

In using the machine, if it be assumed that the shoe is held against the member 5, as shown in Figs. 1 and 4 and then is moved in the direction of the arrow *a* in Fig. 6 so as to cause the member 5 to follow the contour of the last, the frictional engagement between the marginal portion 4 of the shoe upper and the under face of the member 5 will tend to pull the marginal portion 4 of the upper in the direction opposite to the arrow *a* thus distorting the upper and preventing perfect lasting of the shoe. In order to counteract all this distortion of the marginal portion of the upper, I propose to rotate the member 5 positively and in such a direction that the rotation thereof will offset the tendency to distort the upper above referred to. For thus rotating the member 5 I have shown it as rotatably secured to a gear 25 which in turn is fast on a shaft 26 that is rotatably mounted in the support 22. The gear 25 meshes with and is driven by a gear 27 which is fast on a shaft 28 also sustained in the support 22 and this shaft 28 is connected by beveled gears 29 to a horizontal shaft that is journaled in bearings 30 and 31 and provided with gears 32 by which it is driven from a shaft 33 journaled in the frame 9. This shaft 33 in turn is driven from the shaft 19 by suitable gears 34.

With this arrangement the member 5 is rotated in the direction of the arrow in Fig. 6 and as a result, when the shoe is fed, as shown by the arrow *a*, the dragging movement of the upper against the member 5 will be overcome by the rotation of the member 5 and thus the upper will be lasted without being distorted.

In order to permit the adjustment of the support 22 on the frame, as above described, I propose to make the shaft journaled in the bearings 30, 31 in two sections having a telescopic relation. These two shaft sections are indicated at 35 and 36 respectively. The shaft section 36 has the tubular portion 37 into which the end of the shaft section 35 extends, said shaft section 35 having a pin 38 operating in a slot 39 formed in the tubular portion 37. In this way a driving con-

nexion is always provided for rotating the member 5 but at the same time the support 22 with its bearing 30 can be adjusted on the frame without interfering with such driving connections.

70

I claim:

1. In a machine of the class described, the combination with a supporting member adapted to support the edge portion of the sole of a shoe, of means coöperating with said supporting member to beat together the marginal portions of the upper and sole of the shoe, and means to rotate said supporting member.

75

2. In a machine of the class described, the combination with a supporting member adapted to support the edge portion of the sole of a shoe, of means coöperating with said supporting member to beat together the marginal portions of the upper and sole of the shoe, and means to rotate said supporting member about an axis perpendicular to the plane of the sole of the shoe.

80

3. In a machine of the class described, the combination with a supporting member having a flat face to support the marginal portion of the sole of a shoe, of reciprocating means coöperating with said supporting member to press together the marginal portions of the sole and the upper, and means to rotate said supporting member about an axis perpendicular to said face.

85

4. In a machine of the class described, the combination with a supporting member having a flat face to support the marginal portion of the sole of a shoe, of reciprocating means coöperating with said supporting member to press together the marginal portions of the sole and the upper, and means to rotate said supporting member about an axis perpendicular to said face, and in such a direction that the portion of the supporting member which engages the upper moves in the direction in which the shoe is fed.

90

5. In a machine of the class described, the combination with a supporting member adapted to support the edge portion of the sole of a shoe and to force the upper into the angle between the side of a last and a projecting portion of the shoe sole, of means to coöperate with said supporting member to press together the marginal portions of the upper and the sole of the shoe, and means to rotate said supporting member.

95

6. In a machine of the class described, the combination with a supporting member adapted to support the edge portion of the sole of a shoe and to force the upper into the angle between the side of a last and a projecting portion of the shoe sole, of means to coöperate with said supporting member to press together the marginal portions of the upper and the sole of the shoe, and means to rotate said supporting member in such a direction that the portion of the supporting

100

105

110

115

120

125

130

member which engages the upper moves in the direction in which the shoe is fed.

7. In a machine of the class described, the combination with a supporting member adapted to support the edge portion of the sole of a shoe while on a last, of means co-operating with said supporting member to

beat together the marginal portions of the upper and sole, and means to rotate said supporting member.

10 In testimony whereof, I have signed my name to this specification.

ANGELO PERRI.
